BUILDING CONSTRUCTION

Elmer W. Marten, Seattle, Wash.

Application December 9, 1944, Serial No. 567,486

14 Claims. (Cl. 108—1)

1

My invention relates to a precast building construction.

An object of my invention is to provide a building construction wherein all elements including pillars, arch beams, purlins and roof structure are all in the form of precast units which may be formed on the site of the construction or in a central plant.

Another object is to provide a building construction of this character, which is capable of extremely quick erection with virtually no tools except means to lift the units into place, and which may be readily and quickly erected by unskilled or semi-skilled workers.

A further object is to provide a building construction which may be employed as a permanent or temporary building, in the first instance the building construction having, inherently, a low depreciation factor; in the latter instance the various units being readily dismantled, then readily transported and reassembled on other sites.

A further object is to provide a building construction which incorporates novel precast purlin or rafter units and connecting means between the purlin units and their supporting arches.

Further objects of the invention will appear hereinafter.

The invention consists in the novel parts and combination of parts to be described hereinafter, all of which contribute to produce an efficient building construction.

A preferred embodiment of the invention is described in the following specification, while the broad scope of the invention is pointed out in the appended claims.

In the drawings:

Fig. 1 is a fragmentary, transverse sectional view of my building construction showing one of the arch units complete and portions of adjacent arches.

Fig. 2 is an enlarged fragmentary sectional view through 2—2 of Fig. 1, with a portion of the concrete broken away to illustrate the manner in which the arch members are joined.

Fig. 3 is a fragmentary plan view of the roof slabs.

Fig. 4 is a fragmentary perspective view of the roof slabs viewed from their under sides.

Fig. 5 is a fragmentary sectional view through 5—5 of Fig. 1, showing the purlins and arch members, the roof slabs, however, being omitted.

2

Fig. 6 is a bottom view of the purlin members and showing the manner in which they are joined in end-to-end relation.

Fig. 7 is a fragmentary sectional view taken through 7—7 of Fig. 1, showing the manner of cross bracing between rows of arch units.

Fig. 8 is a fragmentary, transverse sectional view of a modified form of my arch members arranged to form a flat surface for supporting an upper floor.

With reference to Fig. 1, foundation piers 1 are appropriately located to support arch members 2. Each arch member is substantially Y-shaped, forming a pier leg 3 and a pair of arch legs 4 defining an obtuse angle. Each arch member is formed of precast concrete with suitably positioned reinforcing rods therein. The lower end of each pier leg is rounded as indicated by 5, to seat or anchor in sockets 6 provided in the foundation piers 1. Each Y-shaped arch member is provided with arch hinge reinforcing 7 molded in the extremity of each arch leg 4, as shown in Fig. 2. The reinforcing of adjacent arch members overlaps and receives a common hinge pin 8. The reinforcing 7 protrudes from their arch legs so that when the arches are joined, there is a space to insert the pins 8. This space is afterwards closed by grouting 4a.

The upper side of each arch leg 4 is straight, and slopes upwardly from the pier leg 3. Molded on this upper side are several purlin shoulders 9. The side of each shoulder facing toward the upper end or extremity of the arch leg 4 is disposed at right angles to the upper surface of the arch.

The arch members 2 are joined together in parallel rows, and these rows of arches are connected by purlin units 10. The purlin units are precast concrete beams containing reinforcing and are rectangular in cross-section. They are adapted to rest on the upper sides of the arch legs 4 and abut the shoulders 9. The shoulders reach above the centers of gravity of the purlin units, so that although inclined from the horizontal when resting on the upper surfaces of the arch legs, they are prevented from falling sidewise by the purlin shoulders.

The reinforcing provided in each purlin unit includes an end reinforcing angle iron member 11. One of such members projects from one of the lower corners of each end of each purlin unit. The remaining lower corner at each end of each

purlin unit is provided with a recess 12 which accommodates the projecting angle member of the adjacent purlin unit so that the units may be disposed in end-to-end relation. Junctures between adjacent purlin units are located over the arch members as shown in Fig. 5. The reinforcing angle members 11 are provided with pairs of depending lugs 13 which overhang the sides of the arch legs 4. As shown in Fig. 7, cross bracing 31 in the form of tension members, draws the rows of ends toward each other and causes the lugs 13 to bear against the sides of the arch members and place the purlin members under compression.

At the plane of abutment of two arch members, 15 their respective arch legs 4 join in obtuse angular relation. It is preferred that the purlins 14 positioned adjacent thereto be L-shaped in cross-section, to form laterally extending legs 15 which abut each other along their extremities, which 20 extremities coincide with the juncture between the arch legs 4. The upright portions of the purlin units 14 are similar in cross-section to the purlin units 10. The pairs of purlin units 14 define a V-shaped trough in which is fitted a 25 series of gutter slabs 16, the under sides of which conform to the legs of the purlin units 14 and the upper sides of which form a gutter channel.

The purlin units 10 and 14 are covered by pan roof slabs 17 and cover roof slabs 18. The roof slabs are flat with slightly tapering sides along which are provided side flanges 19 and 20. The pan roof slabs 17 and cover roof slabs 18 may be identical in shape and size, except that the pan roof slabs are provided at their wider or upper ends with depending retainer lugs 21. The lugs 21 may extend the entire width of the pan roof slabs, or may occupy only portions thereof. The roof slabs are formed of precast reinforced concrete and the convergence of the flanged sides is such that the smaller end of each slab may telescope partially in the larger end of the adjacent slab. The pan roof slabs 17 are placed so that the lugs 21 overhang the purlin units 10 so that the upper pan roof slab drains into the lower, that is, the wider ends of the pan roof slabs are uppermost. The cover roof slabs 18 are positioned with their wider ends downward, and telescope into each other as do the pan roof slabs. When the roof slabs are assembled, mastic or other suitable sealing material is placed between the joints. A narrow ridge covering plate 22 extends over and between the upper margins of the roof slabs of adjacent arch members.

With reference to Fig. 8, the arch construction 41 herein illustrated, is essentially the same as the construction shown in Figs. 1 and 7, in that it comprises a pier member 42 and arch arms 43. In this construction, however, the upper faces of the arch arms 43 are horizontal so that when the arches are joined end-to-end a flat surface is provided for the support of floor structure. With this arrangement continuous reinforcing 44 may extend from end-to-end of the cross members. The arches are joined by the means shown in Fig. 2.

All of the elements which comprise the building construction are capable of being precast so that the assembly involves little more than placing the elements in position. Very few tools are required, although a crane is desirable to lift the arch members into position. Once assembled an extremely rigid structure is provided. The structure may be permanent, or if desired, used tem-

porarily and disassembled for transportation and reassembly at a new site.

Many other embodiments of the invention may be resorted to without departing from the spirit of the invention.

I claim:

1. A building construction, comprising: arch members including column elements seated at their base ends and upwardly and laterally directed arch elements connected at their extremities with the arch elements of adjacent arch members, and abutment shoulders disposed in spaced relation along the upper side of said arch elements, said arch members arranged in parallel rows; purlin units connecting parallel disposed arch members and adapted to lay against the sides of said abutment shoulders, each purlin unit including reinforcing members projecting from its ends adapted to fit into the ends of other purlin units when said purlin units are disposed in end-to-end relation, said reinforcing members having means adapted to overhang the sides of said arch elements to restrain said purlin units against end movement relative to said arch members.

2. A precast building construction, comprising: similar precast arch members each including a column element adapted to be anchored at its lower extremity, and at least one arch element 30 adapted to be pivotally connected to the arch element of an adjacent arch member, said arch members arranged in parallel rows; precast purlin members extending between and connecting parallel disposed arch members; reinforcing members anchored in the extremities of said 35 purlin members and protruding therebeyond, said purlin members having recesses molded in their extremities to receive the reinforcing members of abutting purlin members whereby said 40 purlin members may extend in end-to-end relation across several arch members; and means depending from said reinforcing members adapted to overhang the sides of said arch elements to restrain said purlin members against end movement relative thereto.

3. A building construction, comprising: arch members adapted to define a series of alternate obtuse peaks and valleys, there being integral shoulder elements along the sloping upper sides 50 of said arch members; purlin units connecting parallel disposed arch members and adapted to lay against the sides of said abutment shoulders, each purlin unit including reinforcing members projecting from its ends adapted to fit into the 55 ends of other purlin units when said purlin units are disposed in end-to-end relation, said reinforcing members having means adapted to overhang the sides of said arch elements to restrain said purlin units against end movement relative to said arch members.

4. A building construction, comprising: arch members including upwardly and laterally directed arms connected at their extremities to define a series of peaks and valleys; precast 65 purlin members extending between and connecting parallel disposed arch members; reinforcing members anchored in the extremities of said purlin members and protruding therebeyond, said purlin members having recesses molded in their 70 extremities to receive the reinforcing members of abutting purlin members whereby said purlin members may extend in end-to-end relation across several arch members; and means depending from said reinforcing members adapted to overhang the sides of said arch elements to

restrain said purlin members against end movement relative thereto.

5. A building construction, comprising: precast arch members arranged in parallel rows and defining a series of alternate obtuse peaks and valleys; precast L-shaped valley purlins disposed along said valleys with their leg members confronting to define a gutter base; precast trough-shaped gutter members laid along said gutter base, other precast purlin members of rectangular cross-section disposed in parallel relation on the slopes of said arch members; abutment shoulders molded integrally along the upper sides of said arch members to engage the valley facing sides of said purlin members and extending above their centers of gravity whereby said purlin members rest in stable equilibrium on said arch members, and precast pan and cover slabs positioned across said purlin members and said L-shaped purlins from said peaks to said valleys and adapted to drain into said gutter members.

6. A building construction, comprising: precast arch members arranged in parallel rows and each including, integrally, a central column and upwardly and laterally directed arms; journal elements at the extremities of said arms and said column, the arms being joined end-to-end by their journal elements to form alternate peaks and valleys, abutment shoulders molded in spaced relation along the upper sides of said arms; precast purlin members of rectangular cross-section extending between the rows of said arch members and adapted to rest on edge upon said arms and against said shoulders, said shoulders extending above the mid points of said purlin members whereby said purlin members rest in stable equilibrium; a foundation element for each arch member, including journal means mating the journal element of the corresponding column for pivotally supporting its corresponding arch member.

7. A building construction, comprising: precast arch members arranged in parallel rows and defining a series of alternate obtuse peaks and valleys; precast L-shaped valley purlins disposed along said valleys with their leg members confronting to define a gutter base; precast trough-shaped gutter members laid along said gutter base, other precast purlin members of rectangular cross-section disposed in parallel relation on the slopes of said arch members; abutment shoulders molded integrally along the upper sides of said arch members to engage the valley facing sides of said purlin members and extending above their centers of gravity whereby said purlin members rest in stable equilibrium on said arch members, and precast pan and cover slabs positioned across said purlin members and said L-shaped purlins from said peaks to said valleys and adapted to drain into said gutter members; reinforcing elements protruding from the ends of said purlin members, said purlin elements having recesses molded therein to receive the reinforcing elements of other purlin members positioned in end-to-end relation therewith, said reinforcing elements equipped with depending devices adapted to fit over the arms of said arch members to limit said purlin members against end movement relative to said arch members.

8. A building construction, comprising: precast arch members arranged in parallel rows and including upwardly and laterally directed arms joined to form alternate peaks and valleys, abutment shoulders molded in spaced relation along the upper sides of said arms; precast purlin mem-

bers of rectangular cross-section extending between the rows of said arch members and adapted to rest on edge upon said arms and against said shoulders, said shoulders extending above the mid points of said purlin members whereby said purlin members rest in stable equilibrium, reinforcing elements protruding from the ends of said purlin members, said purlin elements having recesses molded therein to receive the reinforcing elements of other purlin members positioned in end-to-end relation therewith, said reinforcing elements equipped with depending devices adapted to fit over the arms of said arch members to limit said purlin members against end movement relative to said arch members.

9. A precast building construction, comprising: a plurality of precast arch units arranged in rows and each arch unit including a column member and laterally directed arch arms, terminating in journal elements defining the corners of a symmetrical triangle with the apex thereof directed downwardly, the arms of said arch members being pivotally joined in end-to-end relation to form said rows; a series of integral abutment shoulders along the upper side of each of said arch arms; and precast purlin members extending between the rows of said arch members and resting against said shoulders; a foundation member for each arch unit, each foundation member including a journal element coacting with the journal element at the extremity of the column member of the corresponding arch unit.

10. A precast building construction, comprising: a plurality of precast arch units arranged in rows and each arch unit including a column member and laterally directed arch arms, and a series of integral abutment shoulders along the upper side of said arch arms; precast purlin members extending between the rows of said arch members and resting against said shoulders; means for interlocking said purlin members in end-to-end relation; and means for securing said purlin members and arch arms together against relative movement along the longitudinal axes of said purlin members.

11. A building construction, comprising: a plurality of precast arch members, each arch member including, integrally, a downwardly tapering column and laterally directed tapered arms; journal elements at the extremities of said arms and said column; said arch members adapted to be pivotally connected end-to-end by the journal elements at the extremities of said arms; foundation members adapted to support said columns, each foundation member including a mating journal element cooperating with the journal elements of the corresponding columns to afford pivotal support for said arch members.

12. A building construction, comprising: a plurality of precast arch members, the extremities of each arch member defining the apexes of a triangle symmetrical about a vertical axis with one apex directed downward; journal elements at each of the apexes defining extremities of said arch member; a foundation member supporting each arch member by its downwardly directed extremity, each foundation member including a journal element mating with the journal element of said extremity to afford pivotal support for said arch member; the remaining extremities of said arch members adapted to be pivotally connected together in end-to-end relationship.

13. A construction as set forth in claim 11 wherein said arch members are arranged in rows

and the laterally directed arms thereof include purlin spacing means; and wherein precast purlin members extend between said rows of arch members and fitting said spacing means.

14. A construction as set forth in claim 12 wherein said arch members are arranged in rows and each arch member defines purlin supporting surfaces extending between its lateral extremities; wherein purlin spacing means are incorporated in said supporting surfaces; and wherein purlin members extend between said rows of arch members and coact with said spacing means.
